UNITED STATES PATENT OFFICE.

JAMES R. CARDWELL, OF CHICAGO, ILLINOIS.

BRAKE-SHOE.

SPECIFICATION forming part of Letters Patent No. 663,958, dated December 18, 1900.

Application filed August 10, 1899. Serial No. 726,744. (No model.)

To all whom it may concern:

Be it known that I, JAMES R. CARDWELL, a citizen of the United States, and a resident of Chicago, Cook county, Illinois, have invented 5 a certain new and useful Improvement in Brake-Shoes, (Case No. 2,) of which the following, taken in connection with the accompanying drawings, is a specification.

My invention relates to that type of brake-10 shoe which employs an insert of white or hard cast-iron or other suitable material embedded in a casting of soft iron or other like material. If inserts of this kind are made of such a width as to cover the proper amount of the 15 face of the shoe, the parts or walls of the body of the shoe which are at the sides and ends of the insert are necessarily rather thin. One result of this is that in service they are liable to be chipped out or broken.

One object of my invention is, broadly 20 stated, to overcome the above-mentioned difficulty, and this I do by constructing my insert with recesses arranged at intervals along the outer edge thereof adapted to receive a 25 portion of the metal of the body of the shoe in such a manner as to form strengthening parts or buttresses for the thin outer portion of the shell.

Another feature of my invention is the construction of said recesses of such a shape as 30 will form a dovetail opening with which the metal of the body of the shoe along the edge or side wall thereof will interlock, thereby greatly strengthening the construction of the 35 shoe as a whole.

Another object of my invention is the provision of an insert for brake-shoes having a plurality of cellular openings therein arranged with their axes along parallel lines, so that 40 they may be readily drawn from the sand, and having the outer diameter or size of the cellular openings larger than the inner, so that as the metal of the body of the shoe fills the cells the insert will be securely and rigidly 45 held in the shoe and serve to greatly strengthen the same.

The above, as well as such other objects as may hereinafter appear, I attain by means of the construction shown in the accompanying 50 drawings, in which—

Figure 1 shows a face view of a brake-shoe insert constructed in accordance with my in-

vention, the outline of the body of the shoe being indicated around the insert by dotted lines. Fig. 2 is a section through the insert, 55 taken on the line 2 2 of Fig. 1. Fig. 3 is a section on the line 3 3 of Fig. 1. Fig. 4 is a view showing a part of a shoe having an insert provided with recesses on its edges and buttresses for the walls of the shoe having 60 dovetail engagement with the recesses; and Fig. 5 shows a portion of a shoe having a cellular insert made in accordance with my invention, the cells or chambers being of a different shape from those shown in the other 65 views.

In the construction of my insert-plate 6 I form the openings or cells with the diameter or size of that part which is adjacent to the face of the shoe, as indicated at 7, considerably larger than the diameter or size of the bottom of the cellular openings, as indicated at 8. This, as clearly appears in Fig. 3, allows the metal body of the shoe to flow into the cells or chambers of the insert and form 75 a dovetail connection therewith, whereby the strength of the insert is imparted to the shoe.

At intervals along the outer edge of the insert I arrange recesses 9, partly to take away a certain portion of the wearing-face 80 of the hard insert at the edge thereof and partly to permit the metal body of the shoe to flow into the recesses and form buttresses 10 therein, which greatly strengthen the side walls of the body of the shoe and prevent the 85 breaking away thereof in service. As shown in the drawings, I also provide such buttress or supporting parts at the corners of the insert and also at the ends.

In Fig. 4 I have shown an insert-plate with- 90 out cellular openings, but provided with recesses along its edge, the recesses being set in a sufficient distance or shaped in such a way as to form a dovetail connection with the buttress parts of the side wall of the shoe, as 95 clearly indicated at 11. By this means the side wall is prevented from springing outwardly and separating from the insert.

In Fig. 5 the insert is shown as having openings of a honeycomb or hexagonal shape, 100 but somewhat elongated, and also provided with the buttress 10, arranged at intervals along the sides, corners, and ends.

Having thus described my invention, what

I claim as new, and desire to secure by Letters Patent, is—

1. A brake-shoe having an insert-plate, recesses arranged in the edges of said plate, and buttresses formed by the metal of the side wall of the shoe filling said recesses, said buttresses having dovetail connection with said insert-plate, substantially as described.
2. A brake-shoe having an insert-plate embedded therein, said plate being provided

with cellular openings filled by the metal of the body of the shoe, said openings having axes extending along parallel lines substantially as specified, whereby to facilitate the formation of the mold therefor.

JAMES R. CARDWELL.

In presence of—

PAUL CARPENTER,
PAUL SYNNESTVEDT.
